[57] CLAIM

The ornamental design for a toothbrush, as shown and described.

DESCRIPTION

FIG. 1 is a front elevational view of a toothbrush showing my new design;

FIG. 2 is a rear elevational view thereof;

FIG. 3 is a top plan view thereof;

FIG. 4 is a bottom plan view thereof;

FIG. 5 is a side elevational view, the opposite side being a mirror image thereof;

FIG. 6 is a sectional view taken along line 6—6 of FIG. 2;

FIG. 7 is a sectional view taken along line 7—7 of FIG. 1;

FIG. 8 is a front elevational view of a second embodiment of the design shown in FIG. 1;

FIG. 9 is a rear elevational view thereof;

FIG. 10 is a top plan view thereof;

FIG. 11 is a bottom plan view thereof;

FIG. 12 is a side elevational view, the opposite side being a mirror image thereof;

FIG. 13 is a sectional view taken along line 13—13 of FIG. 8;

FIG. 14 is a sectional view taken along line 14—14 of FIG. 8;

FIG. 15 is a front elevational view of a third embodiment of the design shown in FIG. 1;

FIG. 16 is a rear elevational view thereof;

FIG. 17 is a top plan view thereof;

FIG. 18 is a bottom plan view thereof;

FIG. 19 is a side elevational view, the opposite side being a mirror image thereof;

FIG. 20 is a sectional view taken along line 20—20 of FIG. 15; and

FIG. 21 is a sectional view taken along line 21—21 of FIG. 15.
